CLAIM

The ornamental design for a educational game set as shown and described.

DESCRIPTION

Figure 1.1 is a front plan view of an educational game set comprising a building module of ten bricks, according to an embodiment of our new design;

Figure 1.2 is a back plan view of the educational game set according to the embodiment of Figure 1.1;

Figure 1.3 is a first side plan view of the educational game set according to the embodiment of Figure 1.1;

Figure 1.4 is a second side plan view of the educational game set according to the embodiment of Figure 1.1;

Figure 1.5 is a top perspective view of the educational game set according to the embodiment of Figure 1.1; and

Figure 1.6 is a top perspective view of the educational game set according to the embodiment of Figure 1.1.

The claim is directed to the collective appearance of the articles shown in Figures 1.1-1.6.
